BENNO VOM EIGEN, OF NEWARK, NEW JERSEY, ASSIGNOR TO AUGUST GOERTZ & CO., A CORPORATION OF NEW JERSEY.

SAFETY-CATCH FOR BAG-FRAMES.

1,108,430.

Specification of Letters Patent. Patented Aug. 25, 1914.

Application filed December 20, 1913. Serial No. 807,632.

To all whom it may concern:

Be it known that I, BENNO VOM EIGEN, a citizen of the United States, residing at Newark, in the county of Essex and State of New Jersey, have invented certain new and useful Improvements in Safety-Catches for Bag-Frames; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in safety-catches for bag-frames; and, the present invention relates, more particularly, to a novel means in the form of a safety-holding catch for use with the separable members of the usual lock or bag-fastener employed with the frame-sections of bag-frames of the several kinds, and especially with chatelaine bags.

The invention has for its principal object to provide in connection with the two members of a bag-fastener of the general construction herein set forth, a novel and simply constructed, as well as a readily manipulated locking or holding device, which is pivotally connected with one of the said fastener-members, and is adapted to positively retain the two members of the bag-fastener in their locked engagement, until the said locking or holding device is manipulated and is released by the operator from its engagement with the other member of the bag-fastener.

Other objects of this invention not at this time more particularly enumerated will be clearly understood from the following detailed description of the present invention.

With the various objects of the present invention in view, the said invention consists, primarily, in the novel safety-catch for bag-frames hereinafter set forth; and, the invention consists, furthermore, in the novel arrangements and combinations of the several devices and parts, as well as in the details of the construction of the said parts, all of which will be more fully described in the following specification, and then finally embodied in the clauses of the claims which are appended to and which form an essential part of this specification.

The invention is clearly illustrated in the accompanying drawings, in which:

Figure 1 is a front elevation of a bag-frame and its closing catch or bag-fastener provided with a safety retaining or locking means, all made according to and embodying the principles of the present invention. Fig. 2 is a top-edge view of the central portions of the bag-frame-sections, the closing catch or bag-fastener thereof, and the safety-lock or catch employed with said fastener, the said parts being represented in their closed relation, and the said view being made on a considerably enlarged scale. Fig. 3 is an elevation of the parts represented in said Fig. 2, looking in the direction of the arrow *x* in said Fig. 2; and Fig. 4 is a similar view of the same parts, but the safety catch or lock being shown in its disengaged relation with the members of the bag-fastener. Fig. 5 is a transverse section of the device, said section being taken on line 5—5 in said Fig. 3, looking in the direction of the arrow *y*; and Fig. 6 is a similar sectional representation of the device, said section being taken on line 6—6 in said Fig. 4. Fig. 7 is a side elevation of the locking post used with one of the members of the main bag-fastener, the post being shown detached from said member; Fig. 8 is an elevation of said post, looking in the direction of the arrow *z* in said Fig. 7; and Fig. 9 is another elevation of the post, looking in the direction of the arrow *u* in said Fig. 7.

Similar characters of reference are employed in all of the said above described views, to indicate corresponding parts.

Referring now to the several figures of the drawings, the reference-characters 1 and 2 indicate the two hinged frame-sections of any usual construction of bag-frame, and the reference-characters 3 and 4 indicate the two members of a suitable bag-fastener or closing catch adapted to be suitably secured upon the upper central portions of the respective bag-frame-sections 1 and 2. The member 3 in this case is substantially of oval or elliptical marginal configuration, having a correspondingly formed opening 5, and a lower straight marginal edge-portion 6 which rests upon the upper face of the frame-section 1, and is permanently secured to said frame-section, preferably, by

means of rivet-lugs 7 which extend downwardly from said edge-portion 6 and are passed through suitable holes in the said frame-section 1 and then riveted over or up-set upon the lower face-portion of the said frame-section.

Suitably secured upon the upper central face-portion of the frame-section 2, by means of its rivet-lugs 8, or in any other 10 suitable manner, is the member or shank-plate 4, said shank-plate being suitably provided with a locking or retaining post, as 9, which has a knob-shaped end, as 10, or other suitably formed enlargement, and projects 15 laterally from said shank-plate 8 in a direction toward the said member 3, so as to enter the opening 5 of said member, when the two frame-sections 1 and 2 are brought into their closed relation. One means of 20 securing said post 9 to the shank-plate 8 is by means of a rivet-lug 11, in the manner shown in Figs. 5 and 6 of the drawings, the said post 9 being made with a flat surface-portion 12 and an off-set 13, forming an 25 engaging lip which is adapted to be sprung into separable holding engagement with the edge-portion 14 of the member 3, in the manner represented in Figs. 1, 3, 4, 5 and 6 of the drawings. When the said post is in 30 its position relative to the frame-section 2 then the said flat part 12 and the off-set 13 are located upon the under part of the said post. Upon its opposite and upper part the 35 said post is made with another flat surface-portion 15 and an off-set 16, also forming an engaging lip. As shown in said Figs. 5 and 6 of the drawings, the flat part 15 is narrower than the flat part 12, so that the 40 two retaining lips 16 and 13 are differently spaced with relation to each other, as clearly shown and for the purposes hereinafter more fully specified.

The previously mentioned member 3 is provided at one of its ends, as at 17, with a 45 rearwardly extending pivot-pin 18, upon which is pivotally mounted a suitably formed locking or retaining lever, as 19, said lever being provided with a knob or post 20 serving as a fingerpiece for the 50 proper manipulation of said lever, and for moving its lower marginal edge-portion 21 into or out of its locking or retaining engagement with the retaining lip 16 of the post 9, when the two frame-sections 1 and 2 55 are in their closed relation, as will be clearly evident from an inspection of the several figures of the drawings. That the end-portion of the lever 19 which is provided with the knob or fingerpiece 20, 60 when in its closed relation with the two members of the bag-frame fastener proper and with the locking or retaining post 9 thereof, may be held in such closed relation against accidental displacement, 65 the said lever is provided upon that side

directly opposite the said knob or post 20 with a suitable projection or protuberance, as 22, indicated in dotted outline in Fig. 2 of the drawings, which springs into holding engagement with a proper recess or depression 23 in the other end-portion 24 of the member 3, the lever being frictionally held in its closed position by the relation of the several parts of the complete safety-catch. By raising the lever or arm 19 and pressing upon the knob 10 upwardly, the two fastener-members 3 and 4 are readily brought into their separated relation, and the bag-frame section may be moved into their open relation, as will be clearly understood.

The herein-above described device is very simple in its construction and in its operation, and is neat in its appearance.

I am aware that some changes may be 85 made in the general arrangements and combinations of the various devices and parts, as well as in the details of the construction of the said parts, without departing from the scope of the present invention as set 90 forth in the foregoing specification and as defined in the clauses of the claims which are appended to the said specification. Hence, I do not limit my present invention to the exact arrangements and combinations 95 of the various devices and parts as described in the said specification, nor do I confine myself to the exact details of the construction of the said parts, as illustrated in the accompanying drawings.

I claim:—

1. The combination with the hinged members of a bag-frame, and its closing catch comprising a pair of members, one of said members having a locking post-receiving opening, and the other member being provided with a locking post adapted to enter said opening and engage a portion of said first-mentioned member, and a locking lever pivotally connected with said first-mentioned member, said lever being adapted to be brought into holding engagement with a portion of said locking post.

2. The combination with the hinged members of a bag-frame, and its closing catch comprising a pair of members, one of said members having a locking post-receiving opening, and the other member being provided with a locking post adapted to enter said opening and engage a portion of said first-mentioned member, a locking lever pivotally connected with said first-mentioned member, said lever being adapted to be brought into holding engagement with a portion of said locking post, and means connected with said pivoted lever adapted to be brought into separable holding engagement with another portion of said first-mentioned member to prevent accidental separation of the parts.

3. The combination with the hinged members of a bag-frame, and its closing catch comprising a pair of members, one of said members having a locking post-receiving opening, and the other member being provided with a locking post adapted to enter said opening and engage a portion of said first-mentioned member, a locking lever pivotally connected with said first-mentioned member, said lever being adapted to be brought into holding engagement with a portion of said locking post, and means connected with said pivoted lever adapted to be brought into separable holding engagement with another portion of said first-mentioned member to prevent accidental separation of the parts, consisting of a projection extending from one side of said lever adapted to be sprung into a receiving depression with which the said first-mentioned member is provided.
4. The combination with the hinged members of a bag-frame and its closing catch comprising a substantially elliptical fastener member provided with a locking post-receiving opening, and a second post-carrying member, a post extending laterally from said post-carrying member, said post being provided on opposite sides with flattened parts and retaining lips, said flattened parts being of different widths, said locking post being adapted to enter the perforation in said elliptical fastener member, and the lip adjacent to the larger flattened post-portion being adapted to be brought into retaining engagement with a part of the marginal edge-portion surrounding the opening in said elliptical fastener member, a locking lever pivotally connected with said elliptical fastener member, said lever being adapted to enter upon the narrower flattened post-portion and engage the retaining lip adjacent to said narrower flattened post-portion.
5. The combination with the hinged members of a bag-frame and its closing catch comprising a substantially elliptical fastener member provided with a locking post-receiving opening, and a second post-carrying member, a post extending laterally from said post-carrying member, said post being provided on opposite sides with flattened parts and retaining lips, said flattened parts being of different widths, said locking post being adapted to enter the perforation in said elliptical fastener member, and the lip adjacent to the larger flattened post-portion being adapted to be brought into retaining engagement with a part of the marginal edge-portion surrounding the opening in said elliptical fastener member, a locking lever pivotally connected with said elliptical fastener member, said lever being adapted to enter upon the narrower flattened post-portion and engage the retaining lip adjacent to said narrower flattened post-portion, and means connected with said pivoted lever adapted to be brought into separable holding engagement with another portion of said elliptical fastener-member to prevent accidental separation of the parts.

In testimony, that I claim the invention set forth above I have hereunto set my hand this 19th day of December, 1913.

BENNO VOM EIGEN.
